UNITED STATES PATENT OFFICE

WILLIAM G. SHELTON, OF ST. LOUIS, MISSOURI

HAIR-WAVING APPARATUS

Application filed August 15, 1929. Serial No. 386,004.

My invention relates to the art of hair waving and consists in a novel clamp and heating device to be used in the permanent waving of hair.

5 One of the objects of my invention is to produce waves closer to the scalp of the user than the devices of the prior art have been able to produce.

Another object of my invention is to protect the scalp of the user from injury due to heating of the metallic portions of the clamp or descent of moisture.

Another object of my invention is to provide a clamping member and a curling rod 15 and means to tighten the strand of hair on the rod after its application to the clamp and to securely hold the rod against the clamping member.

Another object of my invention is to provide a quickly replaceable jaw face and insulating pad for a jaw of a hair clamp to be used with heaters.

In the accompanying drawings which illustrate selected embodiments of my invention—

Figure 1 is an end elevation of the assembled structure.

Figure 2 is a side view of the same without the heater or the hair wound on the rod.

30 Figure 3 is a top view of the clamping structure.

Figure 4 is a vertical section taken on the line 4—4 of Figure 2 showing the hair wound on the rod and the supply unit applied over the same.

Figure 5 is a view corresponding to Figure 4 showing a modification of my invention.

Figure 6 is a perspective view of the jaw 40 facing pad element.

The scalp of the customer is indicated at S and T is a strand of hair. P is a supply pad. The strand will be gripped adjacent to the scalp by a pair of clamping jaws 1 and 5 having felt or other heat insulating members A and B between them and the scalp of the customer.

The two jaws of the clamp are hinged together at 8 by bar 7 secured to one end of member 5. Suitable catch elements 10 and 13

are provided at the unhinged ends of jaw 1 and jaw 5.

The sharpest and most permanent waves are those produced in the hair adjacent to the metallic curling rod which contacts directly with the hair. The portion of the strand nearest the scalp is necessarily spaced from the curling rod and in order to produce a sharp wave in this portion of the strand, I have provided one of my clamping jaws with a metallic flange 5a of heat conducting material, and arranged to contact with the lower portion of the strand of hair. This flange will be heated by the steam generated within the supply pad in the usual manner.

Clamping jaw 1 is a U-shaped metallic member having a lower leg 1a, an upper leg 1b and a back face 1c. The legs of jaw 1 extend inwardly toward the clamping face of the opposing jaw 5.

A removable insulating member 2 of rubber or like material, has lips 2a and 2b, a face 2c, an upwardly extending flange 2d, and a pocket between lips 2a and 2b adapted to receive the lower leg 1a of jaw 1 so that lips 2a and 2b lie respectively above and below leg 1a. Face 2c is presented to the clamping surface of opposing jaw 5 and flange 2d extends upwardly between leg 1b and the clamping surface of opposing jaw 5.

Clamping jaw 5 is mounted on a base 3 of bakelite or other suitable insulating material and is secured thereto and spaced above the base by rivets 4 and washers 11 or other suitable means. Member 5 is a heat conducting member and has a downwardly extending portion 5a and an upwardly extending curving flange 5b.

Flange 5b, in conjunction with the heater and supply unit P, is adapted to form the first wave of the strand T much nearer the scalp than is possible with the devices of the prior art.

The above clamping structure is provided with a pawl 14 which is mounted on member 7. A curling rod shown at 15 has a ratchet 17 at one end which is engaged by pawl 14 as the rod is rotated to wind the hair. The engagement of the pawl and the ratchet prevents the rod from unwinding and loosening.

the roll of hair. The tension on the hair and the action of the pawl against the ratchet are such as to hold the rod, wound with hair, against the clamp.

5 To apply the device to a strand of hair, the clamp is applied to the strand T close to the scalp S and bars 1 and 5 are locked together by elements 10 and 13. The curling rod is then applied to the outer end of the 10 strand and turned to wind the hair on the rod until the same is adjacent to the clamping jaws where the pawl 14 engages the ratchet 17 and holds the rod 15 from unwinding when the same has been wound enough to 15 create a tension on the strand T. Then the supply element P is placed around the hair wound on the rod, and the lower edges of the supply are pushed under the roll of hair so that the supply contacts with the metallic 20 member 5. The heater is then placed over the supply. Heat is transmitted from the heater through the moist supply unit to the metallic member 5, along flange 5b to the strand of hair between the base of the clamp 25 and the beginning of the outermost spiral of the roll of hair on rod 15.

The yielding jaw face 2 adapts itself to variations in the thickness of the strand of hair, tightly clamps the same against the opposing 30 surface without breaking or cutting the hairs, and provides a jaw face which may be easily renewed from time to time without replacing the entire clamp. Due to the deep pocket K, between lips 2a and 2b, for receiving 35 the jaw leg 1a there is a large surface frictionally engaging the faces of the leg. The pocket is closed at its ends to more securely engage the jaw leg.

In the modification disclosed in Figure 5, 40 the clamping member 20 corresponds to member 1 in Figure 4, but is a metallic bar instead of a channel, and is enclosed by a heat insulating member 21 consisting of a tube of rubber or like material.

45 The opposite clamping member 24 has a depending offset 25 from the lower end of which the curved flange 26 extends towards the other jaw and upwardly constituting an inner form for the portion of the strand of 50 hair usually contained between clamp jaws which are not metallic and hence do not contribute to the waving of the hair. The curvature of this flange extends even closer to the scalp than that shown in Figure 4 but lacks 55 the desirable feature of a straight surface squarely opposing the right hand jaw which characterizes the preferred form of my invention.

60 In each form of my invention, the heat conducting flange fits tightly against the rubber face covering the opposing jaw to seal the clamping jaws so that no moisture can pass through the same to the scalp of the user. The felt pads act as a further seal for such 65 moisture but their main function is to insu-

late the scalp from the heated parts of the device. As previously mentioned, the metallic flange forms a curved heat conducting surface which is effective in producing a wave nearer the scalp than can be produced by the 70 curling rod.

Obviously, the details of the described structure may be varied without departing from the spirit of my invention and I contemplate the exclusive use of such modifications 75 as come within the scope of my claims.

I claim:

1. In a clamp for a permanent wave device, a set of clamping jaws, a hair engaging element comprising a sheet of heat conducting material bent substantially as shown and mounted on one of said jaws and extending lengthwise of said jaw and above the level of the top of said jaw. 80

2. In a permanent wave device, a heater, a clamp below the same, and a hair engaging element comprising a sheet of heat conducting material bent substantially as shown and disposed intermediate said heater and clamp. 85

3. In a permanent wave device, a heater, a clamp, and a hair engaging element of heat conducting material having a portion intermediate said heater and clamp and having a portion extending below the level of the top of said clamp. 90

4. In a permanent wave device, a heater, a supply unit, a pair of clamping jaws adapted to grip a strand of hair near the scalp of the user, one of said jaws having a surface of heat conducting material, said surface being in contact with said supply unit and with said strand of hair at the base of said jaws, said elements cooperating to transmit heat from said heater to said strand of hair between said jaws. 95

5. In a permanent wave device, a pair of clamping jaws adapted to grip a strand of hair near the scalp of the user, one of said jaws having a surface presenting to said strand of hair a curved flange of heat conducting material, and means for heating said flange to wave the hair adjacent to said flange. 100

6. In a permanent wave device, a pair of clamping jaws adapted to grip a strand of hair near the scalp of the user, the inner surface of one of said jaws being covered with heat insulating material, the inner surface of the other jaw being formed of heat conducting material, and means for heating said heat conducting material to wave said strand of hair between said jaws. 115

7. In a permanent wave device, a pair of clamping jaws adapted to grip a strand of hair near the scalp of the user, heat insulating pads on said jaws adapted to rest on the scalp of the user, the clamping face of one of said jaws being covered with heat insulating material, the clamping face of the other jaw being formed of heat conducting material, 120

130

- and means for heating said heat conducting material to wave said strand of hair between said jaws, said jaws and said pads cooperating to form a seal to prevent the passage of steam or heat to the scalp of the user.
8. In a permanent wave device, a pair of clamping jaws adapted to grip a strand of hair near the scalp of the user, a metallic flange forming the side of one of said jaws presented to said strand of hair, a heater, and means for conducting heat from said heater to said flange to wave said strand of hair from the bottom of said clamp to the top of said flange.
9. In a permanent wave device, a pair of clamping jaws adapted to grip a strand of hair near the scalp of the user, heat insulating pads on said jaws adapted to rest on the scalp of the user, the clamping surface of one of said jaws being covered with heat insulating material, the other jaw being composed of a strip of heat insulating material resting on said insulating pad, a metallic member parallel with said strip, means holding said strip and said member in spaced position, a metallic flange integral with said member, spaced from said insulating strip and curving up from the same, said flange opposing the surface of the other jaw when said jaws are clamped together, and extending above the surface of said other jaw to contact said strand of hair along the entire surface of said flange.
10. In a permanent wave device, a pair of clamping jaws adapted to grip a strand of hair near the scalp of the user, heat insulating pads on said jaws adapted to rest on the scalp of the user, the clamping surface of one of said jaws being covered with heat insulating material, the other jaw having as a clamping face a flange of heat conducting material, a pawl on said clamping jaws, a curling rod, a ratchet thereon, said ratchet being adapted to lock said rod to said clamping jaws when a strand of hair has been gripped by said jaws and the remainder of the strand tightly wound on said rod, a supply unit wrapped over said strand of hair wound on said rod, a heater placed over said hair and supply unit, whereby heat passing from said heater through said supply unit to said hair wound on said rod and to said hair adjacent to said flange waves the hair near the scalp of the user.
11. In a permanent wave device, a pair of metallic clamping jaws, one of said jaws being an inwardly facing U-shaped member, a removable rubber element covering one leg of said member and having outwardly facing lips adapted to fit around said leg, said rubber member having a face presented to the clamping surface of the other jaw, and a flange between a second leg of the first jaw and the clamping surface of the second jaw.
12. In a permanent wave device adapted
- to be applied to a strand of hair, a heater, a heat conducting element below said heater, an element between said heater and said heat conducting element through which heat passes to said heat conducting element to wave said strand near the scalp of the user.
13. In a hair waving device, a clamp comprising a set of jaws and including a jaw of channel shape section, and a removable jaw face of yielding insulating material having a pocket for receiving one leg of said jaw section.
14. In a hair waving device, a clamp comprising a set of jaws and including a jaw of channel shape section, and a removable jaw face of yielding insulating material having a pocket for receiving one leg of said jaw section and an upstanding flange for engaging the edge of the other leg of said jaw section.
15. A removable jaw face for a hair waving clamp comprising a rubber bar having an elongated pocket in one side for receiving a flat metal jaw element, the ends of said pocket being closed to position said element lengthwise of said bar.
16. A removable jaw face for a hair waving clamp comprising a rubber bar with a felt pad secured to its lower face, said rubber bar having an elongated pocket in one side for receiving a flat metal jaw element, the ends of said pocket being closed to position said element lengthwise of said bar.
- In testimony whereof I hereunto affix my signature this 13th day of August, 1929.
- WILLIAM G. SHELTON.
